UNITED STATES PATENT OFFICE.

JOHN H. HUNT, OF DAYTON, OHIO, ASSIGNOR TO THE DAYTON ENGINEERING LABORATORIES COMPANY, A CORPORATION OF OHIO.

IGNITION SYSTEM.

Application filed September 3, 1918. Serial No. 252,316.

To all whom it may concern:

Be it known that I, JOHN H. HUNT, a citizen of the United States of America, residing at Dayton, county of Montgomery,

5 State of Ohio, have invented certain new and useful Improvements in Ignition Systems, of which the following is a full, clear, and exact description.

This invention relates to ignition systems 10 for internal combustion engines and the like.

One of the objects of the invention is to provide an ignition system including an ignition coil which is constructed in such 15 a manner that the coil can be placed in the vicinity of metallic bodies, such as the cast-iron cylinders of the engine, without substantially affecting the operation of the coil.

20 Another object of the invention is to provide an ignition coil in which for a given ratio of secondary and primary turns the best ratio of transformation can be obtained.

25 A further object of the invention is to provide an ignition system including an ignition coil in which the inductance can be varied in accordance with the operation of the engine with which the system is 30 employed.

More particularly it is an object to provide an ignition coil which while the engine is running at a low speed will have a high inductance in order to obtain a hot 35 spark while the engine is starting or running slowly, and devices for reducing the inductance of the coil at high engine speed in order to obtain a faster working coil, so that although a large number of sparks 40 are required at high speed the efficiency of the spark will be maintained at a maximum.

Other and further objects of the present 45 invention will be apparent from the following description, reference being made to the accompanying drawings, in which certain embodiments of the invention are shown.

In the drawings:

50 Fig. 1 is a wiring diagram of an ignition system embodying the present invention;

Fig. 2 is a wiring diagram of an ignition system embodying a modified form of the invention;

55 Fig. 3 is a wiring diagram of a modified form of ignition coil included in the present invention; and

Fig. 4 is a side elevation partly in section of an ignition timer, including controlling devices forming a part of the present invention.

Referring to Fig. 1, 10 designates as a whole an ignition coil including a C-type core 11. Said core 11 includes main core portions 12 and 13 which are separated by a relatively narrow gap 14, and yoke portions 15 and 16 which are connected together by auxiliary cores 17 and 18. The primary ignition winding 20 is wound upon the main 70 cores 12 and 13 and has one end thereof connected by a wire 21 with an ignition switch 22 which is connected by wire 23 with a battery 24 which is grounded at 25. The other end of the primary winding 20 is connected by wire 26 with a timer 27 which is connected by wire 28 with a rheostat resistor winding 29. A wiper 30 cooperates with the resistor 29 and is grounded at 31.

80 The secondary ignition winding 32 is wound around the main cores 12 and 13 and the primary winding 20 and has one end thereof grounded through the battery by means of the wire 21, switch 22 and 85 wire 23, and the other end thereof is connected by wire 33 with a distributor 34 which is connected with the various spark plugs 35 of the engine (not shown).

85 A controlling winding 40 is mounted on the auxiliary core 17 and one end thereof is grounded at 41 and a controlling winding 42 is mounted on the auxiliary core 18 and is grounded at 43. Both windings 40 and 42 are connected in parallel with 90 each other and both together in series with the wire 44 which is connected with a rheostat resistor 45. The wiper 46 cooperates with the wiper 45 and said wiper 46 is connected by wire 47 with wire 21. 100

Wipers 30 and 46 may be mounted on the same lever, or, as shown in Fig. 4 may be separately mounted and may be moved together by the same actuating element.

Referring to Fig. 4, 50 designates as a whole a timer unit which includes a housing 51 in which a shaft 52 is journaled by means of bearings 53 and 54. Shaft 52 carries a gear 55 which meshes with the gear 56, said gear 56 being connected with the crank shaft of the engine by any suitable means (not shown). The shaft 52 is of hollow construction and is provided with a spiral slot 57. A cam shaft 58 having a straight slot 59 is mounted within the upper end of the shaft 52. Sleeve 60, mounted to slide axially of the shaft 52, carries a pin 61 which passes diametrical- 15 ly across the sleeve and through the spiral slot 57 and the straight slot 59. Said pin 61 serves as a driving connection between the shaft 52 and the shaft 58, and by reason of the cooperation of the pin 61 with the sliding sleeve 60 in the members 52 and 20 58, the sliding movement of the said sleeve 60 will cause relative angular movement between the shaft 58 and the shaft 52. This movement is effected automatically according to the speed of the engine by means of a centrifugal member 62 which is pivoted at 63 upon the shaft 52 and is connected by a link 64 with the sleeve 60. It is evident that as the speed of the shaft 52 increases the member 62 will tend to assume a substantially horizontal position and thereby cause the sleeve 60 to move upwardly to cause the displacement of member 58 relatively to the shaft 52. This 30 movement of sleeve 60 due to centrifugal force acting on the member 62 is resisted by spring 65 interposed between sleeve 60 and the bearing 54.

A cam 70 is mounted on the shaft 58 and serves to effect the engagement of timer contact members 71 and 72 which are included as elements of the timer 27. Upon the upper end of the shaft 58 is mounted a distributor rotor 73 which is shown diagrammatically in Fig. 1 as cooperating with stationary contacts 74.

The wipers 30 and 46 are pivoted upon the frame 51 at 80 and 81 respectively. Wiper 30 engages with the sleeve 60 whereby the longitudinal movement of said sleeve will cause a pivotal movement of the wiper 30. The movement of the wiper 30 is transmitted to the wiper 46 by means of the link 82.

The resistor 29 is mounted upon a spool 83 which is mounted on a shaft 84 carried by the frame 51. Spool 83 is provided with a crown tooth ratchet 85 which cooperates with a pawl 86 carried by a lever 87 which is mounted at 88 upon the frame 51. The wiper 30 is provided with a lug 89 which upon the upward travel of the wiper 30 strikes against the portion 90 of the lever 87 and causes the pawl 86 to move the ratchet 85 a distance corresponding to the space be-

tween adjacent ratchet teeth. The spring 91 cooperates with the teeth 85 to prevent the turning of the spool 83 in a reverse direction. The resistor 45 is mounted in the same fashion as the resistor 29. The particular mounting of the resistors 29 and 45 is not a part of the present invention but is described and claimed in the patent of Charles F. Kettering and William A. Chryst, No. 1,272,055 issued July 9, 1919.

It is evident from the foregoing description of the timer unit 50 that as the speed of the engine varies the position of the wipers 30 and 46 will vary in accordance therewith. The construction and arrangement is such that as the speed increases the wipers will be actuated to cut resistance out of the circuits in which the resistors are included.

The operation of the device shown in Fig. 1, and the supposed underlying theory, is as follows: The ignition switch 22 is closed and the engine is started in the usual manner. When timer contacts 71 and 72 are closed current will build up in the primary winding 20, thereby creating a magnetic field in the vicinity of the windings 20 and 32. By making the magnetic circuit C shaped with a very short air gap within the exciting winding, the reluctance of the magnetic circuit is concentrated within the winding thereby causing the energy of the coil to be stored in said air gap and within a small fringe about it. By carrying the density as high as possible for the core iron used it is possible to store a large amount of energy in a comparatively small space.

Thus by storing the energy within the gap, when this energy is released, the magneto-motive force released will be expended within the coils 20 and 32. The magneto-motive force effective at the ends of the coil 20 and 32 is reduced to a minimum, and therefore there is substantially no tendency for leakage to occur as in the case of the conventional type coil (having a straight bar core around which the windings are placed). This characteristic of the type of coil disclosed embodying the present invention permits of location close to metallic bodies which are magnetic, as the iron cylinders of an internal combustion engine, or non-magnetic as a brass base or housing for the coil. The conventional type coil does not permit of such location without seriously interfering with the operation thereof. An exploration of the field of the conventional type coil would show that most of the energy of the coil is concentrated close to the ends of the core. The introduction of any masses of metal in this region would cause trouble. If iron is introduced, the field will be distorted and there will be a possibility that the inductance of the coil will be greatly increased. If the inductance is increased and the coil is any-

thing like an economical construction, the core will become saturated before the usual maximum current is reached. As a result of the high inductance at low currents under high speed running conditions, the current will be held down to a smaller value than would otherwise be reached, while at lower speeds there will be no more energy in the coil than if the masses of iron were not there. Since practically the total magneto-motive force of the primary is effective at the ends of the primary core, the tendency of leakage flux through the masses of iron in the vicinity is very high. If, on the other hand, instead of iron there is brass in the field, the field will not be distorted, but owing to a comparatively low resistance of the metal, eddy currents will be set up in the metal at the time of the break of the primary ignition circuit, and practically all of the energy represented by this part of the flux will be lost. But in the type of coil disclosed embodying the present invention, none of the foregoing disadvantages of the conventional type coil are present.

It is obvious that if the iron of the external magnetic circuit of the type of coil disclosed could be removed during the operation of the coil, it would be possible to reduce the inductance of the coil very materially. If this iron of the external circuit can be saturated so thoroughly that it can not carry any of the ignition coil flux the effect will be practically the same as if the iron were removed. It is, of course, essential that this saturation of the magnetic circuit be carried out in such a way that there are no windings about any part of the magnetic circuit which can act as short circuits with respect to the voltage induced by the flux change caused by the break of the current in the primary.

This result is accomplished in the following manner.

When the engine is running slowly, all the resistor windings 45 are in circuit and very little current will flow to the windings 40 and 42. As the engine speed increases wiper 46 will be automatically moved to cut out resistance and to permit an increasing amount of current to flow through said windings 40 and 42. It will be noted that the magnetic circuit is completed through the yokes 15 and 16, and the auxiliary cores 17 and 18 act in parallel as far as the flux due to the primary is concerned. Since the change of flux due to the winding 20 will be substantially the same in cores 17 and 18, and since the windings 40 and 42 have an equal number of turns and are connected as shown in Fig. 1, the electro-motive forces generated in said windings 40 and 42 by the pulsations of the main flux will be opposed, and will be substantially balanced, and substantially no current

will be induced in the windings 40 and 42. With the windings 40 and 42 thus arranged, a direct current sent through them tends to send flux around cores 17 and 18 and the end yokes without directly affecting the magnetic or electric circuit as at the left of the line A—A.

By reason of the ability of regulating the inductance of the type of coil disclosed in the manner described, an ignition system including said coil possesses certain advantages over the system using the conventional type coil. The coil can be constructed so as to have the minimum inductance available when the coils 40 and 42 are fully excited, said inductance being of the proper value for the highest speed work that is required of the coil. At low engine speeds the coil can be run without any excitation in the regulating coils 40 and 42 with a result that, the inductance being higher, the ignition coil produces a hotter spark for starting or for low speed running conditions. Where the inductance of a coil cannot be varied according to the speed of the engine construction of the coil is restricted between certain limits. The limit on one hand is the inductance required at starting but which would be too high for high speed conditions; and the limit on the other hand is the inductance required at high speed which would be far too low to obtain a hot spark at starting or slow speed conditions. The inductance of the coil of the conventional type is somewhere between these limits but cannot be the ideal value for all engine speeds. But with the type of coil disclosed it is possible to reduce the inductance 30% of the initial value, permitting the inductance for slow speed work to be over 40% greater than would be otherwise possible where the inductance could not be varied, and, at the same time, providing for ignition required for highest speeds. It was found by experiment that the striking distance of the spark at high speeds was better in case of type of coil disclosed than the conventional type, when operated at the same speed.

It is not essential that the current through the primary winding be regulated in accordance with the speed of the engine, but where the connections are as shown in Fig. 1 it may be desirable to do so in order that a certain proportion between the current passing through the winding 20 and current passing through the windings 40 and 42 may be maintained at certain speeds. It is not essential that the windings 40 and 42 be connected in parallel but it has been found that this connection is preferable.

The control of the current passing through the windings 40 and 42 may be effected in other ways than in the manner shown in Fig. 1 and already described. The

regulating current passing through windings 40 and 42 may be switched on only when high speed is reached by a manually controlled switch located somewhere in the connections between the battery and the windings, or the switch may be controlled by a centrifugal governor. Another way in which the windings 40 and 42 may be controlled is shown in the modified form 10 of the invention shown in Fig. 2.

Referring to Fig. 2, 100 refers as a whole to a shunt field third brush regulating generator having an armature 101, brushes 102, 103 and 104, and field windings 105 and 106. 15 The positive brush 102 of the generator 100 is connected with the reverse current relay 107 which is connected by wire 108 with the wire 23 connected with the battery 24. The negative brush 103 of the generator 100 is 20 grounded at 109 thereby effecting a connection with the negative side of the battery through the ground 25. The armature 101 is rotated in the direction of the arrow 110. The shunt windings 105 and 106 are connected 25 between the third brush 104 and the brush 102. The third brush is connected by wire 44 with the windings 40 and 42 which are grounded at 41 and 43 respectively. When 30 the generator is operated, the third brush 104 being at a higher potential than the brush 103, current will flow through the wire 44 and the windings 40 and 42 to ground connection 41 and 43 respectively and back through ground 109 to the brush 35 103. When the generator is running slowly with slow engine speeds, the potential difference between brush 104 and brush 103 will be very small, consequently the windings 40 and 42 will have very little regulating 40 effect. As the speed of the generator increases with increased engine speed the field will be distorted due to armature reaction with a result that the potential difference between brushes 104 and 103 will be materially increased. This regulating effect is 45 taken advantage of in previous devices to reduce the battery charging rate of high speeds, since the output of the generator is reduced with the reduction of field excitation at high speeds. But while the field excitation is reduced due to the drop in potential between brushes 102 and 104, the potential between 50 104 and 103 will increase with increased engine speed and this characteristic can be taken advantage of to cause an increased amount of current to flow through the windings 40 and 42. It has been found that an ignition system embodying the type of coil described in combination with a third 55 brush regulating generator will have very satisfactory characteristics. Thus the desired effect obtained by regulating the inductance according to speed can be produced automatically through the agency of a third brush regulating generator which is gener-

ally employed in the electrical equipment of an automobile engine.

Referring to Fig. 3 in which a modified form of the ignition coil is shown, 120 indicates as a whole the core including main 70 cores 121 and 122, yokes 123 and 124 and auxiliary cores 125 and 126. The cross sectional areas of cores 125 and 126 and yokes 123 and 124 are equal, and each is equal to one-half the cross sectional area of the main 75 cores 121 and 122. The primary winding 20 and the secondary winding 32 are wound around the main cores 121 and 122, and the connections between these windings, distributor, timer and battery are the same as 80 shown in Fig. 1. The regulating windings 40 and 42 are wound around the cores 125 and 126 respectively. The winding 40 is grounded at 41 and the winding 42 is grounded at 43 as is the case of the system 85 shown in Fig. 1. The wire 44 connecting this wire in parallel may be connected with the rheostat 35 or with the third brush 104. The operation of these coils is substantially 90 the same as the coils shown in Figs. 1 and 2 95 but it has been found that the characteristics of the coil shown in Fig. 3 may be better for some purposes than the characteristics of the coil shown in Figs. 1 and 2. This may be due to the fact that the end yokes 123 and 124 may be entirely saturated by the regulating 100 windings 40 and 42 while in the case of the cores shown in Figs. 1 and 2 that portion of the cores to the left of the line A—A cannot be saturated by the windings 40 and 105 42. The following dimensions of the core and windings are given for purpose of illustration only, and it is to be understood that the invention is not restricted to these dimensions or to the exact proportions between 110 them. The primary winding 20 may have 250 turns of number 21 wire, the secondary winding 20 12,500 turns of No. 36 wire, and the windings 30 and 32 each may have 1,125 turns of No. 28 wire. The main core cross 115 sectional area is .500 square inch and the sectional area of the yokes 123 and 124 of the cores 125 and 126 is .125 square inch. The outside dimensions of the cores are 3.175 inches by 4.125 inches by .500 inch. The 120 coil having these dimensions was found to have an inductance of substantially 10 millihenries at low speed and that the inductance could be reduced to 6 millihenries at high speed. It was found by experiment 125 that the coil just described has a better steady striking distance at high speeds than a coil having a core of the shape shown in Fig. 1 and having slightly less copper and more iron, and a better steady striking distance at high speeds than a coil of the conventional type which was constructed to furnish ignition under the same conditions. It was found that the characteristics of the 130 coil shown in Fig. 3 having the dimensions

referred to are very satisfactory at low speeds as well as high speeds.

While the forms of mechanisms herein shown and described constitute preferred forms of embodiments of the invention, it is to be understood that other forms might be adopted, all coming within the scope of the claims which follow:

1. In an ignition system, the combination with a source of current, and sparking devices; of an ignition coil including windings adapted to be connected with the source and sparking devices, and including a core; and provisions for changing the inductance of the coil by varying the reluctance of the material of the core.

2. In an ignition system for internal combustion engines, the combination with a source of current and sparking devices; of an ignition coil having a C-type core with a fixed gap; and engine operated means for varying the reluctance of the core in response to variations in engine operation.

3. In an ignition system for internal combustion engines, the combination with a source of current and sparking devices; of an ignition coil including a core and windings adapted to be connected with the source and sparking devices; and means acting automatically in accordance with the operation of the engine for saturating a portion of the core whereby to vary the inductance of the coil.

4. In an ignition system for internal combustion engines, the combination with a source of current and sparking devices; of an ignition coil including a core and windings adapted to be connected with the source and the sparking devices; auxiliary windings cooperating with the core for saturating a portion thereof; and means acting automatically in accordance with the operation of the engine for varying the amount of current flowing through the auxiliary windings.

5. In an ignition system for internal combustion engines, the combination with a source of current and sparking devices; of an ignition coil including a core and windings adapted to be connected with the source and sparking devices; auxiliary windings cooperating with the core for saturating a portion thereof; a rheostat connected with the auxiliary windings and the current source; and means controlled by the speed of the engine for actuating the rheostat wiper.

6. In an ignition system for internal combustion engines, the combination with a source of current and an ignition timer; of an ignition coil including a core and windings adapted to be connected with the source and ignition timer; auxiliary windings cooperating with the core for saturating a portion thereof; and an engine operated device for controlling the timer and for controlling

the current passing through the auxiliary windings, in accordance with the speed of the engine.

7. In an ignition system for internal combustion engines, the combination with a source of current and an ignition timer; of an ignition coil including a core and main windings adapted to be connected with the source and ignition timer; auxiliary windings cooperating with the core for saturating a portion thereof; and an engine operated device for controlling the timer and for controlling the current passing through the auxiliary windings, and for controlling the current passing through the main windings.

8. In an ignition system for internal combustion engines, the combination with a source of current and an ignition timer; of an ignition coil having a C-type core with a fixed gap; and engine actuated means for varying the timing of the ignition and the inductance of the coil in response to changes in engine speed.

9. In an ignition system for internal combustion engines, the combination with a source of current and an ignition timer; of an ignition coil adapted to be connected with the source and timer; and means controlled by the speed of the engine for controlling the timer and for varying the inductance of the coil and for varying the exciting current of the coil.

10. In an ignition system for internal combustion engines, the combination with a source of current and sparking devices of an ignition coil including main windings cooperating with the source and sparking devices and a core including a main core portion cooperating with the main windings and auxiliary core portions of equal magnetic dimensions arranged in parallel with each other and both together in series in the magnetic circuit containing the main core portion; auxiliary windings cooperating with the auxiliary cores; and means for automatically controlling the passage of current through the auxiliary windings in accordance with the operation of the engine.

11. In an ignition system, the combination with a unidirectional continuous current source, and sparking devices; of an ignition coil including windings adapted to be connected with the source and sparking devices, and including a core; auxiliary windings cooperating with said core and connected to said source; and means for varying the current flowing through said auxiliary windings to vary the reluctance of said core.

12. In an ignition system, the combination with a source of current and sparking devices; of an ignition coil including a core, and exciting windings adapted to be connected with the source and sparking devices; and means for varying the degree of saturation.

tion of a portion of the core whereby to vary the reluctance of the material of said core.

13. In an ignition system, the combination with a source of current and sparking devices; of an ignition coil including a core and exciting windings adapted to be connected with the source and the sparking devices; auxiliary windings cooperating with the core for saturating a portion thereof; and means 45
5 for varying the amount of current flowing through the auxiliary windings whereby to vary the reluctance of the material of said core.
14. In an ignition system for internal-combustion engines, the combination with a current source and a timer; of an ignition coil including a core and exciting windings adapted to be connected with said source and said timer; auxiliary windings cooperating 50
10 with said core for saturating a portion thereof; and means for controlling the timer and for varying the current in said auxiliary windings.
15. In an ignition system for internal-combustion engines, the combination with a current source and a timer; of an ignition coil including a core and exciting windings adapted to be connected with said source and said timer; and means for varying the degree of saturation of a portion of said core 60
20 and for controlling the ignition timer.
16. In an ignition system for internal-combustion engines, the combination with a source of current and an ignition timer; of an ignition coil having a C-type core with a fixed gap; and means for simultaneously varying the reluctance of the core and for controlling the ignition timer. 70
30
17. In an ignition system for internal-combustion engines, the combination with a current source and a timer; of an ignition 75
40

coil including a core and exciting windings adapted to be connected with said source and said timer; and means for varying the inductance of the coil, for controlling the current passing through the exciting windings and for controlling the ignition timer.

18. In an ignition system for internal-combustion engines, the combination with a current source and a timer; of an ignition coil 55
50 including a core and exciting windings adapted to be connected with said source and said timer; and means varying the inductance of the coil and for controlling the current passing through the exciting windings. 55

19. In an ignition system for internal-combustion engines, the combination with a current source and a timer; of an ignition coil including a core and exciting windings 60
60 adapted to be connected with said source and said timer; auxiliary windings cooperating with said core for saturating a portion thereof; and means for varying the current passing through said exciting windings and for varying the current in said auxiliary windings. 65

20. In an ignition system for internal-combustion engines, the combination with a current source and a timer; of an ignition coil including a core and exciting windings 70
75 adapted to be connected with said source and said timer; auxiliary windings cooperating with said core for saturating a portion thereof; and means for controlling the ignition timer, for varying the current passing through said exciting windings and for varying the current in said auxiliary windings.

In testimony whereof I affix my signature.
JOHN H. HUNT.
